UNITED STATES PATENT OFFICE.

FORTUNATO NEVEUX, OF RIVOLI, ITALY, ASSIGNOR TO O. M. I. M. OFFICINA MECANICA INDUSTRIA MAGLIERIA, OF TURIN, ITALY, A COMPANY.

STRIPING APPARATUS FOR CIRCULAR HOSIERY MACHINES.

Application filed March 9, 1923, Serial No. 624,005, and in Italy March 17, 1922.

This invention relates to hosiery knitting machines of the French circular type, and has for its object to provide a device which will be able to make striped hosiery in two colors.

This device has been particularly provided for circular knitting machines with non-radial loop-wheels, i. e., loop-wheels having their axes inclined relatively to the radius of the machine, such machines being adapted to work at considerable speed.

Yarn-feeding devices for hosiery knitting machines are known which supply alternately two yarns, replacing each other at the desired times; but the feeding devices heretofore used are not capable of being employed in hosiery knitting machines of very high speed.

According to this invention, the yarn-changing device comprises two pairs of shears, one of which brings the inoperative yarn to the needles and retires, while the other cuts the operative yarn and retains it, the respective functions of the shears being reversed on the next change of yarn.

Automatic means are provided for independently advancing and opening and closing the shears and causing them simultaneously to move backward and exchange places, and for preventing both yarns being cut at one time by the shears.

In the annexed drawings, forming part of this specification, an embodiment of striping device is shown, by way of example.

Fig. 1 is a perspective view of the entire yarn-changing attachment to be applied to circular knitting machines.

Fig. 2 shows the details of a cam which operates to shift the yarn-shears to insert the new yarn and remove the old.

Fig. 3 shows the details of one of the yarn-shears.

Fig. 4 is a diagram showing the operative relation between the yarn-shears and the operating cam.

Figs. 4^a, 4^b, 4^c, 4^d, and 4^e are similar to Fig. 4 and are views showing the various operating positions of the shears.

Fig. 5 is a transverse sectional view of one of the shears.

Figs. 6 and 7 diagrammatically show a front view and a horizontal view of a portion of the circular hosiery knitting machine

(of usual form), to which the striping apparatus of my invention is shown as applied; some structural details having been omitted for the sake of clearness.

Referring, first, to Fig. 1, the apparatus comprises two pairs of cutting and clamping shears 1, 2, radially arranged with respect to the knitting machine and slidably in cylindrical parallel boxes 3, 4, rigidly connected to each other a short distance apart. When it is required that the working yarn in the hosiery be changed for yarn of a different color or quality, the shears 1 (which we will assume to be the foremost in the direction of rotation of the knitting machine) are so arranged, as shown in Fig. 1 and position I Fig. 4, as to move toward the needle row in the knitting machine, and enter upon the needles the end of an inoperative yarn held between the clamping-blades of the cutting and clamping device. Meanwhile, as soon as the shears 1 shall have completed their forward movement and the free end of the yarn carried thereby shall have been caught by the blades of the loop-wheel, the shears 2 (which have been open during the period of such movements of the shears 1) will spring forward, in their turn, and suddenly close, thus cutting the active yarn and clamping its free end.

Both shears, to perform the operations described, are slidably fitted, as above stated, in the respective boxes 3 and 4. Springs 5, Fig. 3, tend to force the shears forward, said springs being compressed between the inner ends of the boxes and the rear ends of the supporting-rods of the shear-blades, which rods are guided within the boxes by guide-pins 6 sliding in slots 7, Fig. 1, in the boxes.

Referring, now, to Figs. 3 and 5, each of the shears comprises three blades *a*, *b*, *c*; the blades *b* and *c* being fixed to the supporting-rod or slide, whereof they are extensions, while the blade *a* is pivotally mounted between the blades *b* and *c* to oscillate upon a transverse pivot *d*, and is provided with a sidewise projecting arm *e* bearing a pin *f*. Said three blades are so shaped, as shown in Fig. 5, as to be able to cut a yarn between the blades *a* and *c*, while the free end of the cut yarn is clamped between the blades *a* and *b*.

During the operation before described, the closing of the shears 2 is effected by their pin 2^a impinging against a fixed stop 8.

As soon as both of said operations are completed, both shears will gradually be drawn back out of operative relation to the circular needle row of the knitting machine. During said backward movement, the pin 1^a of the shears 1 will strike against the stop 16, the latter being, like the stop 8, fixed on a stationary transverse head 17 fixedly mounted in front of the shaft 9, stop 16 being so shaped as to force the blade 1^a to open and reach the position shown at 1^a in Fig. 3, say a position like the initial position of blade 2^a of the shears 2, as shown in Fig. 1.

The shears, with their boxes rigidly connected to each other, are so arranged as to be able to turn about a common axis on the axis of shaft 9, radially arranged with respect to the knitting-machine. As soon as said shears are fully returned to rearmost position within the boxes, the latter will rotate 180° around said shaft, in such manner that the shears 2, retaining the free end of a yarn between their blades, as well as the shears 1, being provided with no thread, will exchange places or positions, so as to be ready for the next operation, in the same manner as has been described.

The forward movement of each of the shears independently of the other, and their simultaneous return are obtained and controlled by a cylindrical helical cam 10 (Fig. 2), upon the helical edges 11 and 12 whereof slide the pins 6, preferably provided with anti-friction rollers. It will be understood that the longitudinal steps 13 and 14, not being diametrically opposite each other, will allow one of the corresponding shears to snap forward a little in advance of the other.

The operation of both shears will be more clearly understood by reference to Fig. 4, showing the cylindrical helical cam 10 developed in a plane. The direction of rotation of said cam is shown by the arrow. The shears are shown in full lines in their initial position, indicated by the Roman numeral I, additional positions being shown in dash and dot lines and indicated by further Roman numerals II, III, and IV.

The cam moving in the direction of the arrow in the drawings, the shears 1 will suddenly snap to the position 1'. A little later, the open shears 2 will snap in turn to the position 2' and will be compelled to close by the pin f striking the fixed stop 8, as above stated. The continued movement of the cam 10 will cause both of the shears to move backward gradually, their roller pivots 6 sliding on the inclined or helical edges of the cam. The closed shears 2 will move from position 2' into position I, while the shears 1 are compelled to open by the sta-

tionary stop 16, against which the pin f strikes, while returning from position 1' to position 1''. Both shears thus again have reached their initial positions and also their respective initial open and closed conditions.

The swinging movement of the boxes 3 and 4 around the shaft 9 is effected by the expansion of a spring motor in a casing 15, said spring being wound up during the former operative steps of the apparatus.

The winding up of said spring is obtained, in the example shown, by a radial shaft 18 provided at one end with a pinion 19 controlling by means of the intermediate pinion 20 the pinion 21 of the shaft 9, and meshing also with the pinion 22 on the winding shaft of the spring in the box 15.

At the other end, the shaft 18 is provided with the three-tooth or Geneva device 23, co-operating with a suitable rack, comprising teeth 43 on the rotary bottom plate 44 of the knitting machine, so arranged as to give the shaft 18 the successive partial rotations required.

The shaft 18 is provided with a laterally-projecting retaining-finger 24, engaging a fixed stop hook 25, and a further laterally-projecting finger 26 so arranged as to push away, at certain times, the detent 27, co-operating with the one or the other of two oppositely extending lugs 28, 28 on the integral cross bar connecting the boxes 3 and 4, which lugs may or may not be integral with the cross-bar. The rod 27 is suitably pivoted at 29 upon the supporting-bracket 30 fastened to the knitting-machine body.

Referring, now, to Figs. 6 and 7, the apparatus is fastened by a bracket 30 and a bolt 31 to the upper circular table 32. 33 indicates the needles and 34 the loop-wheel, the blades of which control the taking of thread by each needle, said loop-wheel being only diagrammatically shown in the drawings.

The yarns A and B, shown by different dotted lines, are guided or supported by glass guide-rings, diagrammatically shown by small circles C, such yarns leading respectively to the knitting point D and the shears 1 retaining the end of the inoperative yarn. Said yarns, coming from different bobbins, pass through holes 35 in a horizontal guide-bar 36 adapted to slide alternately in a radial direction with reference to the knitting machine, such movement being sufficient to enable the bar to introduce each of the yarns A and B, at the proper time, between the gears 37 and 38 of the yarn-feeding device. Then, guided by the rings E, suitably arranged, they pass through holes 39, 40 at the lower ends of guide-rods 39, 40 suspended to oscillate in vertical planes radially of the knitting machine.

The shears 1 and 2 are provided with fingers 41, 42, respectively, so bent and of such

length as to be able to strike, while the shears are moving forward in the yarn-cutting movement, against the guide-rods 39 and 40 respectively. In Fig. 7, the finger 42 is shown about to contact with the rod 40; the same would be true for the finger 41 of the shears 1, in connection with the rod 39, after the swinging operation of the connected boxes carrying the shears 1 and 2 has taken place. Thus, when each of the shears (say, for example, the shears 2, Figs. 1 and 7) being open, snaps forward to cut the respective yarn (the yarn A, Figs. 6 and 7), it will press against the rod of the other yarn (the rod 40 of the yarn B) and move the latter forward away from the path of the blades of said shears, thus preventing the non-desired yarn from being cut by accident.

For the sake of clearness in the drawings, 20 the yarn-feeding device and guide-rods 39, 40 have been shown a considerable distance apart from each other and from the main structure of the invention, the fingers 41, 42 having, therefore, a very considerable length. 25 It will, however, be understood that all of those members can be very much reduced in size and may be arranged close to each other, so that the circumferential distance occupied thereby about the periphery of the knitting 30 machine is, in practice, very much smaller than indicated in the drawings.

As said heretofore, the starting of the striping apparatus is effected through the Geneva member 23 (Figs. 1, 6 and 7) carried by the inner end of the shaft 18. Said member is operated by the projections 43 of a rack suitably fixed to the lower turning plate 44 of the knitting machine, in such manner as to co-operate through its circular 40 path with the member 23. The latter is slidably fitted onto the inner end portion of the shaft 18, and kept in its end position by a spring 45, Fig. 1, wound around said inner end portion, the member 23 being in this 45 normal position out of the path of the projections in the rack 43.

Any suitable controlling device may be provided to shift member 23 into the path of projections 43 at the desired time, that 50 is, when the yarn is to be changed from one color to another. Such device forms no part of the present invention and is not herein shown or described.

The operation of the invention is as follows: With the apparatus in the condition shown in the drawing, yarn A of one color is being fed into the knitting machine in the usual manner and the yarn-changing device does not play any part in the operation. However, as soon as a sufficient 55 amount of yarn A has been knitted into the product, the member 23 of the Geneva device will be shifted along the axis of shaft 18 into the path of projections 43 carried by 60 the rotary plate 44 of the knitting machine.

Referring to Fig. 6, assuming that rotary plate 44 is moving to the left, projections 43 will strike against the arms or fingers of member 23 and will cause the member 23, shaft 18 and gear 19 to rotate in a clockwise direction. Gear 21, shaft 9 and cam 10 will also be driven in a clockwise direction by gear 19 through the intermediate gear 20, shears 1 and 2, with their housings 3 and 4, remaining stationary during this 70 movement. As cam 10 begins to rotate, the high portion of cam surface 11 moves out from under pin 6' of shears 1 and allows the shears to be forced forward by spring 5 (see Figs. 2, 3 and 4). The forward movement of shears 1 is stopped by pin 6' striking the low portion of cam surface 12. Referring to Fig. 6, as shears 1 move forward it enters under the row of needles 33 and carries with it the end of the inoperative 80 yarn B, and since the yarn is fed from above the needles, such movement will cause the inoperative yarn to enter the rotating needle row where it will be caught and carried on by the needles. Upon further movement of the cam 10, the high portion of surface 12 moves out from under pin 6' and allows shears 2 to be forced forward by its spring (see Fig. 4, wherein the arrow indicates the direction of travel of the cam). 85

Referring to Fig. 1, the blade 2 of shears 1 is open and as it moves forward pin 2' strikes against the stationary stop 8, thereby operating the shears to cut yarn A and retain the loose end between its blades. 100 Upon continued movement of the cam in a clockwise direction both shears are withdrawn from their forward positions, and as shears 1 moves back pin 1' strikes against fixed stop 16, thereby opening its blade. Member 23 and projections 43 are so designed as to effect a clockwise direction of rotation of cam 10 for 180° only, and after this the member 23 is free to be rotated back in the other direction. During the forward or clockwise rotation of member 23, the spring in housing 15 is put under tension by gear 22 connected with gear 19. Near the end of the clockwise movement of shaft 18, the finger 26 carried thereby engages rod 27 and pushes it out of the path of lug 28 carried by the shears frame. As soon as member 23 becomes free to rotate in an anti-clockwise direction, the spring in housing 15 will begin to unwind and drive 110 gears 19 and 21 in an anti-clockwise direction. Since rod 27 has been pushed out of the path of lug 28, the frame of the shears is free to rotate, and will be rotated in an anti-clockwise direction along with cam 10, 115 to cause shears 1 and 2 to exchange positions.

The connection between cam 10 and the frame of the shears is such as to allow the frame to remain stationary while the cam 120

is rotated in a clock-wise direction, but when the cam rotates in an anti-clockwise direction the frame is carried along with it. This may be any well known one-way drive connection such, for example, as a ratchet and pawl arrangement. With the shears in exchanged positions, shears 2 now occupy the position of shears 1 shown in the drawing and retains the free end of yarn A between its blades ready to be inserted between the needles at the proper time, and shears 1 occupy the position of shears 2, shown in the drawing and has its movable blade open ready to cut and withdraw yarn B at the proper time.

Having thus fully described my invention, what I claim as new and desire to secure by Letters-Patent is:

1. In a circular knitting machine a circular needle row, a yarn-changing device comprising two pairs of shears, one of which brings the inoperative yarn to the needles and retires while the other cuts the operative yarn and retains it, the respective functions of the shears being reversed on the next change of yarn, and means for rotating said pairs of shears about an axis transverse to said needle row whereby each pair of shears is disposed first above and then below said row.
2. In a circular knitting machine a circular needle row, a yarn-changing device comprising two pairs of shears, one of which brings the inoperative yarn to the needles and retires while the other cuts the operative yarn and retains it, the respective functions of the shears being reversed on the next change of yarn, and means for independently advancing and opening and closing the shears and for simultaneously causing them to move axially away from the needle row and exchange places.
3. In a circular knitting machine a circular needle row, a yarn-changing device comprising two pairs of shears, one of which brings the inoperative yarn to the needles

and retires while the other cuts the operative yarn and retains it, the respective functions of the shears being reversed on the next change of yarn, and means for moving the 50 yarn not to be cut out of the path of the cutting shears.

4. In a circular knitting machine a circular needle row, a yarn-changing device comprising two pairs of shears, one of which brings the inoperative yarn to the needles and retires, while the other cuts the operative yarn and retains it, the respective functions of the shears being reversed on the next change of yarn, springs constantly urging forward said shears axially toward the needle row, a cam controlling the position of the shears, means for opening and closing one blade of each pair of shears according to the position given to the shears by the cam, and means for periodically and simultaneously rotating the shears about an 60 axis transverse to the needle row.

5. In a circular knitting machine a circular needle row, a yarn-changing device comprising two pairs of shears, one of which brings the inoperative yarn to the needles and retires, while the other cuts the operative yarn and retains it, the respective functions of the shears being reversed on the next change of yarn, springs constantly urging forward said shears, a cam controlling the position of the shears, means for opening and closing one blade of each pair of shears according to the position given to the shears by the cam, means for periodically causing the shears to exchange places, comprising a rack, a shaft having on it teeth normally out of mesh with the rack, a finger on the shaft cooperating with a stop normally contacting with the shears' carrier, and means for periodically placing the said teeth in the path of the teeth on the rack.

In witness whereof, I have hereunto signed my name.

FORTUNATO NEVEUX.
